TOY

Paul F. Gosswein and Ernst C. Gosswein,
Chicago, Ill.

Application October 4, 1943, Serial No. 504,858

5 Claims. (Cl. 272—52)

This invention relates to toys or playthings and, more particularly, to a child's plaything in the form of a rocking horse.

An object of the invention is to provide a new and improved rocking horse toy or plaything having greater structural strength and resistance to bending and possessing a greater safety factor than similar rocking horse toys heretofore made.

Rocking horse toys have been made heretofore of both metal and laminated wood or so-called wood veneer. However, one of the difficulties experienced with such toys made of metal has resided in the fact that prolonged use thereof and incidental bending causes the metal in the resilient member or spring embodied in the toy to crystallize and eventually break or become unsafe.

Likewise, one of the principal difficulties heretofore experienced in the use of rocking horse toys embodying a resilient member or spring made of laminated wood or so-called wood veneer has resided in the fact that repeated use of rocking horse toys so constructed and repeated rocking thereon by a child has tended to cause the laminations or wooden strips in the spring or resilient member to tend to stretch and separate, with resulting loss of structural strength and safety factors.

Another difficulty heretofore experienced in the use of rocking horse toys embodying a resilient member or spring made of laminated wood has resided in the fact that such springs as heretofore constructed have lacked adequate strength and a sufficient safety factor to withstand prolonged use especially by older and heavier children.

Accordingly, an object of the present invention is to provide a new and improved rocking horse toy embodying a laminated wood spring which is so constructed and arranged that the laminations or wooden plies embodied therein will not spread apart even after prolonged use.

Another object of the invention is to construct the new rocking horse toy in such a manner that the laminated wooden spring or resilient member embodied therein possesses greater structural strength and resistance to breaking than has been possessed by the resilient members or springs of rocking horse toys heretofore made.

Other and further objects of the present invention will be apparent from the following description and claims and will be understood by reference to the accompanying drawing which, by way of illustration, shows preferred embodiments and the principles thereof and what we now con-

sider to be the best mode in which we have contemplated applying those principles. Other embodiments of the invention embodying the same or equivalent principles may be used and structural changes may be made as desired by those skilled in the art without departing from the present invention and the purview of the appended claims.

In the drawing,

10 Fig. 1 is a side elevational view of a rocking horse toy embodying the present invention;

Fig. 2 is a top plan view of the rocking horse toy shown in Fig. 1;

15 Fig. 3 is a front end elevational view of the rocking horse toy shown in Figs. 1 and 2;

Fig. 4 is a view on line 4—4 in Fig. 1, partly in section and partly in elevation;

20 Fig. 5 is an enlarged fragmentary vertical sectional view, on line 5—5 in Fig. 2, showing a preferred construction of the lower front end portions of the upper and lower parts of the laminated wooden members which form the spring embodied in the new rocking horse toy; and

25 Fig. 6 is a fragmentary side elevational view on a reduced scale illustrating a modification of the invention which is especially adapted for use by very young children.

30 A preferred embodiment of the new rocking horse toy is shown in Figs. 1 to 5, inclusive, of the drawing, wherein it is generally indicated at 10, and comprises a pair of spaced transversely and horizontally extending front and rear supporting pedestals or feet 20 and 21, which may be of any suitable design and shape. The resilient member or spring embodied in the new rocking horse toy comprises a runner 12 which extends between the front and rear supporting pedestals 20 and 21, respectively, and is secured thereto in any suitable manner, as by means of countersunk screws. As best shown in Fig. 1 the bottom runner or member 12 embodies an upwardly curved strengthening arch 14 which merges at its front end into the lower front end portion 13 of the bottom spring element 12.

35 The resilient member or spring embodied in the new rocking horse toy also includes an upper spring element 11 having a lower front end portion 27 which extends substantially parallel to and in contacting engagement with the upper surface of the lower front end portion 13 of the bottom runner 12, the lower front end portions 13 and 27 of the spring elements 11 and 12 being secured together rearwardly of the front supporting pedestal 20 by any suitable fastening ele-

ments such as countersunk screws 19. As shown in Fig. 1 of the drawing, the middle and rear portions of the upper spring element 11 extend upwardly in spaced relationship with or relative to the lower spring element 12.

A child's seat 17 is attached to the upper end portion 15 of the upper spring element 11 and a suitable design or decorative member, such as 16, may be mounted upon the upper end portion 15 of the upper spring element 11, adjacent the seat 17, and this design or decorative member 16 may be provided with a pair of handle elements 22 projecting laterally therefrom and where a child using the toy may grasp when upon the seat 17.

Likewise, a suitable foot rest as 18 may be mounted upon and adjacent to the midportion of the upper spring element 11 at a suitable height relative to the handles 22 to accommodate the average child of the particular age group for which the new toy may be designed and intended and the new toy may be made in various sizes and for children of different age groups, if desired.

It will be noted by reference to Fig. 5 that the upper and lower spring elements 11 and 12, respectively, are composed of laminated wood or veneer strips which are suitably glued and pressed together so as to form a structurally strong spring or resilient member. Thus the upper spring element 11 comprises a plurality of wood strips or plies 24, which are preferably made of oak or other suitable hard wood, pressed and glued together, and top and bottom strips 28 and 29 of suitable hard wood, such as birch, are pressed and glued to the top and bottom laminated strips or plies 24.

Similarly, the bottom spring element 12 comprises a plurality of laminated wood or veneer strips 26, such as strips of oak pressed and glued together by means of a suitable adhesive, and these laminated strips 26 are enclosed between top and bottom strips of birch or other suitable hard wood 30 pressed and glued thereto (Fig. 5).

It will thus be seen that in the use of the form of the new rocking horse toy shown in Figs. 1 to 5, inclusive, the weight of a child disposed upon the seat 17 acts, through the lower front end portion 27 of the upper spring element 11 to force the said lower front end portion 27 of the upper spring element 11 downwardly upon the slightly upwardly extending lower front end portion 13 of the bottom spring element 12. Hence, it will be seen that as the upper end portion 15 of the upper spring element 11 and the seat 17 thereon are depressed, by the rocking motion of a child disposed upon the seat 17, the lower front end portion 27 of the upper spring element 11 tends to flatten out the upwardly curved strengthening arch 14 of the bottom spring element 12 and this flattening action upon the strengthening arch 14 effectively absorbs a substantial part of the downward force exerted by the weight and rocking motion of the child upon the seat 17 of the upper spring element 11. Hence it will be seen that the strain upon the laminations 28-24-29 and 26-30 of the lower front end portions of the upper and lower spring elements 11 and 12, respectively, is materially reduced and any tendency to separate which these laminations would otherwise exhibit, particularly after prolonged use, is eliminated.

It will also be observed that the arrangement

of the lower front end portion 27 of the upper spring element 11 in parallel and contacting engagement with the upper surface of the lower front end portion 13 of the bottom spring element 12, and the relationship of these parts to the strengthening arch 14 in the lower spring element 12, renders the new rocking horse toy relatively strong structurally and enables the upper spring element 11 to be flexed or bent repeatedly downwardly without danger of breaking or disconnecting the upper and lower spring elements 11 and 12 at their point of connection 19 or elsewhere.

Fig. 6 of the drawing illustrates a modification 15 of the invention which is especially adapted for use by very young children who might be too timid or afraid to play upon the form of the new toy shown in Figs. 1 to 5, inclusive. Those parts in the form of the invention shown in 20 Fig. 6 which are similar to corresponding or analogous parts in the form of the invention shown in Figs. 1 to 5, inclusive, have been given the same reference numerals followed by the distinguishing reference character or letter *a*.

The form of the invention shown in Fig. 6 25 differs from that shown in Figs. 1 to 5, inclusive, in that the strengthening arch is omitted from the bottom spring member of runner 12a since this form of the invention is intended for use by very small and young children whose 30 weight is not sufficient to require the use of the strengthening arch in the bottom spring member, as is embodied in the form of the invention shown in Figs. 1 to 5, inclusive.

The modification shown in Fig. 6 also differs 35 from that shown in Figs. 1 to 5, inclusive, in that, being intended for use by smaller and younger children, the upwardly extending and 40 seat-supporting portion 15a is arranged closer to the rear portion of the bottom runner 12a than is the case of the corresponding parts in the form of the invention shown in Figs. 1 to 5, inclusive, and the foot rest 18a is arranged upon 45 the bottom runner or spring member 12a, rather than upon the upper spring member 11a. This is for the reason that the very young and small children for whom the form of the invention shown in Fig. 6 is especially intended might be 50 too timid or afraid to place their feet upon the foot rest if and when the latter is mounted upon the upper spring member and such very small and young children will feel more secure in 55 using the form of the new toy shown in Fig. 6 and in the use of which their feet are placed upon the foot rest 18a carried by the bottom runner or spring member 12a.

While we prefer to make the upper and lower 60 spring members 11 and 12 and 11a and 12a of laminated plywood strips glued together since such material is relatively inexpensive and possesses the desired strength and resiliency and other qualities which render it suitable for this purpose, nevertheless, if desired the top and bottom spring members and other parts of the new toy may be made of other materials including suitable metals and plastic or other synthetic materials in either laminated or solid 65 form.

It will thus be seen that the present invention 70 provides a new and improved rocking horse toy which has the desirable advantages and characteristics and accomplishes its intended objects including those hereinbefore specifically pointed

out and others which are inherent in the invention.

We claim:

1. A rocking horse toy comprising spaced front and rear supporting pedestals, a lower resilient spring element extending between and fastened to said supporting pedestals, an upper resilient spring element having a lower front end portion secured to said front supporting pedestal and having middle and rear portions extending upwardly in spaced relationship with said lower resilient spring element and the said rear portion of said upper resilient spring element being provided with a seat for a child, said upper and lower resilient spring elements each being composed of a plurality of wooden plies adhesively laminated together and having lower front end portions secured together rearwardly of said front supporting pedestal and disposed in substantially parallel relationship with and in contacting engagement with each other.

2. A rocking horse toy comprising spaced front and rear supporting pedestals, a lower resilient spring element extending between and fastened to said supporting pedestals, an upper resilient spring element having a lower front end portion secured to said front supporting pedestal and having middle and rear portions extending upwardly in spaced relationship with said lower resilient spring element and the said rear portion of said upper resilient spring element being provided with a seat for a child, said upper and lower resilient spring elements having lower front end portions secured together rearwardly of said front supporting pedestal and disposed in substantially parallel relationship with and in contacting engagement with each other, said lower spring element including an upwardly curved strengthening arch having a front end portion merging into the said lower front end portion of said lower spring element.

3. A rocking horse toy comprising spaced front and rear supporting pedestals, a lower resilient spring element extending between and fastened to said supporting pedestals, an upper resilient spring element having a lower front end portion secured to said front supporting pedestal and having middle and rear portions extending upwardly in spaced relationship with said lower resilient spring element and the said rear portion of said upper resilient spring element being provided with a seat for a child, said upper and lower resilient spring elements having lower front end portions secured together rearwardly of said front supporting pedestal and disposed in substantially parallel relationship with and in contacting engagement with each other, said lower spring element including an

upwardly curved strengthening arch having a front end portion merging into the said lower end portion of said lower spring element, and the said strengthening arch being located in the front half of the said lower spring element relative to the midpoint between the said front and rear supporting pedestals.

4. A rocking horse toy comprising spaced front and rear supporting pedestals, a lower resilient spring element extending between and fastened to said supporting pedestals, an upper resilient spring element having a lower front end portion secured to said front supporting pedestal and having middle and rear portions extending upwardly in spaced relationship with said lower resilient spring element and the said rear portion of said upper resilient spring element being provided with a seat for a child, said upper and lower resilient spring elements having lower front end portions secured together rearwardly of said front supporting pedestal and disposed in substantially parallel relationship with and in contacting engagement with each other, said lower spring element including an upwardly curved strengthening arch having a front end portion merging into the said lower front end portion of said lower spring element, and the said upper and lower spring elements each comprising a plurality of wooden strips adhesively secured together.

5. A rocking horse toy comprising spaced front and rear supporting pedestals, a lower resilient spring element extending between and fastened to said supporting pedestals, an upper resilient spring element having a lower front end portion secured to said front supporting pedestal and having middle and rear portions extending upwardly in spaced relationship with said lower resilient spring element and the said rear portion of said upper resilient spring element being provided with a seat for a child, said upper and lower resilient spring elements each being comprised of a plurality of wooden strips adhesively secured together, and the said upper and lower spring elements having slightly upwardly extending lower front end portions secured together rearwardly of the said front supporting pedestal and disposed in substantially parallel relationship with and in contacting engagement with each other, and said lower resilient spring element having an upwardly curved strengthening arch therein formed as an integral rearward continuation and extension of the said slightly upwardly extending front end portion of said lower spring element.
